UNITED STATES PATENT OFFICE.

NICHOLAS A. BIBIKOV, OF NEW YORK, N. Y.

SANDAL OR SLIPPER.

SPECIFICATION forming part of Letters Patent No. 687,513, dated November 26, 1901.

Application filed September 19, 1900. Serial No. 30,456. (No model.)

To all whom it may concern:

Be it known that I, NICHOLAS A. BIBIKOV, of the city of New York, county of Kings, and State of New York, have invented certain 5 new and useful Improvements in Sandals or Slippers, of which the following is a full, clear, and exact description.

My invention relates to improvements in footwear; and the object of my invention is 10 to produce a very cheap, simple, and easy sandal or slipper which is particularly adapted for use as a bath-slipper or house-sandal, but which may of course be used for any usual purpose. I have found that by taking 15 a length of fibrous cord and shaping it so that the parts shall lie side by side and assume the shape of a slipper sole and vamp and then stitching or otherwise fastening the parts together a very cheap shoe or sandal is made, 20 and this structure is particularly desirable as a bath-slipper, first, because the fibrous material opens up when wet and becomes very soft and elastic, and, second, because the structure described is very cheap. I have 25 found, too, a particularly cheap and reliable means for attaching such a sandal to the foot, and this fastening device can be applied to any ordinary sandal, if desired.

To these ends my invention consists of cer- 30 tain features of construction and combina- tions of parts, which will be hereinafter de- scribed and claimed.

Reference is to be had to the accompanying drawings, forming part of this specification, 35 in which similar characters of reference refer to similar parts throughout both views.

Figure 1 is a perspective view of the sandal or slipper embodying my invention, and Fig. 2 is a cross-section through the fastening- 40 clasp.

The sole 10 and upper 11, the upper con- 45 sisting merely of the vamp, are given substan- tially the usual shape, but are made, prefer- ably, of a fibrous cord 12, an ordinary manila 50 cord being suitable, which cord is laid flat and wound and pressed to the desired shape, so that none of the parts shall overlap, but lie side by side, and when suitably shaped the parts are confined and held together by 55 stitches or other equivalent fastenings. As above remarked, ordinary fibrous cord is pref- erable for this structure; but I do not confine

my invention to such cord, as any cord having the necessary consistency can be used.

The upper consists, as above stated, of a 55 vamp 11, the bottom edge of which is stitched or otherwise fastened to the toe and front portion of the sole 12, and the vamp has a split or open top 14, which is formed partly to make the sandal easy to the foot, partly to 60 make it more attractive to the sight, and partly for the sake of cheapness, as it will be noticed by reference to the drawings that the cord members at the ends of the vamp are doubled and returned upon themselves, as 65 shown at 15, which structure naturally pro- duces the slit or opening 14.

The upper edges of the vamp 11 are stayed by the cross-strap 16, which extends across the slit or opening 14, and the cord forming 70 the vamp is extended to form the fastening- straps 17, which extend back and are attached to the heel of the sole, as shown at 19. The straps 17 are also fastened at their ends to the vamp 11 at the inner edges of the quar- 75 ters—that is, at the end of the slit 14.

A clasp 20 is held to slide on the straps 17, the clasp having ferrule-like parts 21, each embracing a strap 17, and the clasp is located, preferably, near the heel and can be slid up 80 or down, as desired. This clasp can be made of aluminium, tin, or other light material. In fact, it can be made of any suitable mate- rial.

The foot is inserted between the straps 17 85 and the toes thrust into the vamp 11, after which the clasp 20 is pulled up on the back of the heel, thus tightening the straps 17 and holding the sandal or slipper firmly to the foot. It will be observed that this fastening 90 means can be applied to any ordinary sandal.

From the foregoing description it will be seen that the sandal or slipper which I have described is of the simplest structure, that the material is cheap, that it can be easily 95 made, and that it is flexible enough to con- form to all the movements of the foot and to permit such movements to be easily made. It will also be observed that the sandal or slipper described is particularly adapted for 100 bathing purposes, as the sole is not only flat, but is for the most part without an upper, and consequently there is nothing to hold water.

Having thus described my invention, what I claim as new, and desire to secure by Letters Patent, is—

As an improved article of manufacture, a sandal or slipper comprising a sole of fibrous cord, the parts of which are placed side by side, fastened together and made of the requisite shape, a vamp covering the toe portion only and formed likewise of cord, the members being placed side by side, fastened together and shaped to leave an opening at the instep, a stay or strap extending across the

said opening, flexible cords extending from the vamp on opposite sides of the opening to the heel of the sole, and a fastening-clasp connecting the aforesaid straps and slidable thereon.

In testimony whereof I have signed my name to this specification in the presence of two subscribing witnesses.

NICHOLAS A. BIBIKOV.
